COMBINATION GARMENT

Dora Liebert,
Application February 1
1 Claim.

This invention relates to combination garments and more particularly to combined gown and pajama or the like.

It is an object of the present invention to provide a garment of the above type, which comprises trousers with or without blouse section, and a gown, all these parts of which said garment may consist being adapted to be worn in assembled condition.

Another object of the present invention is to provide a combined garment of the above nature comprising a complete outer garment and an inner garment member, said inner garment member being so arranged relatively to the outer garment that when the outer garment is worn in closed condition the inner garment member may be substantially hidden from view, whereas when the outer garment is worn in open condition impression and appearance of a two-part garment is attained.

Still another object of the present invention is to provide respective closure means for outer garment and inner garment member.

A further object of the present invention is to provide a combined garment which comprises an outer garment having the form and shape of a gown, coat or like covering, and an inner garment member or part providing a pair of trousers, pajama or like garment part, which may be connected to the inside of said outer garment, said inner garment part and said outer garment being so arranged with respect to each other that a person, when using said combined garment and with a single operation is completely dressed and does not need any additional garment parts, which is very desirable for emergency cases, air raids, etc.

A still further object of the present invention is to provide a combination garment which can be adapted and used for sport, beach wear, as well as for dressy purposes, which is very attractive, spacious, and very convenient to wear.

Still a further object of the present invention is to provide a combination garment composed of an outer garment and an inner garment member, the outer garment being preferably tailored in coat, gown or similar fashion with or without a hood, and may form a complementary part for the inner garment member which may be built in and attached to the inside of the outer garment.

A further object of the present invention is to provide a combination garment comprising an outer garment, such as a coat, gown, preferably tailored in princess style, and an inner garment

1942, Serial No. 431,295
Cl. 2—71)

member or part, such as blouse part and/or trousers or divided skirt, connected to the inner face of said outer garment, said outer garment and said inner garment member being made of any suitable material or fabric with matching or contrasting colors.

A still further object of the present invention resides in the provision of a combination garment provided with an inner garment part and outer garment, a portion of said inner garment part being attached to seams extending on the inner face of said outer garment, the latter forming a complementary portion of said inner garment part, whereby the style of said outer garment may be utilized in a most economical manner.

These and other objects and advantages of the invention will appear from the following disclosure thereof together with the attached draw-

5 cular hereinafter set forth with the attached drawings which illustrate a certain form of embodiment thereof. This form is shown for the purpose of illustrating the invention, although it is to be understood that the various parts and elements of which the invention consists can be variously arranged and organized provided they come within the scope of the claims.

In the drawings:

Fig. 1 shows a front elevational view of the combined garment made in accordance with the invention.

Fig. 2 shows the garment of Fig. 1 in open condition.

Fig. 3 shows a front elevational view of a combined garment, a part thereof being sidewardly flared. Fig. 4 shows a rear elevational view of the garment.

Fig. 5 shows a sectional view (on an enlarged scale) along line 5-5 of Fig. 1.

Fig. 6 shows a fragmentary sectional view (drawn on a somewhat larger scale) of one leg of the trousers used in connection with the invention.

Fig. 7 is a sectional view in diagrammatic form and taken along line 1—1 of Fig. 1 and at a level just above the crotch of the trousers.

In that form of the embodiment of the invention shown in Figs. 1 to 3, the combination garment made in accordance with this invention and designated by numeral 10 comprises outer garment or coat 11 and inner garment member 12.

Coat 11, in this instance, is of the princess style with the lower, out-flaring part 13. The outer garment 11 has closure means, such as buttons 14. The inner garment member 12 consists of

the trousers 15 and upper or blouse part 16, the latter being sewed with its lower edge 17 to the trousers to form the seam 17a. Complementary fastening means 18 extend from the blouse part 16 to the trousers 15 to open and close the inner garment member 12. The blouse part 16 is attached to the inside 19 of the outer garment 11 along seams 20 and 21, as may be realized from Fig. 3, and may project toward the neck of the wearer, thus being exposed to view at the lapel 22 of the outer garment 11, as clearly seen in Figs. 1 and 2. As indicated in the drawings, trousers 15 and blouse part 16 may be made of a fabric which may differ in color or shade from the material used for the coat 11. As further seen in Fig. 2, trousers 15 are discernible only when the coat 11 is worn in open condition (Fig. 2). Those parts of material forming the trousers 15 extend from respective seams 23c, 23d at the longitudinal side edges 23a, 23b on the inside of the coat 11 to respective seams 24a, 24b positioned at the inner face of the rear panel 30a of the outer garment or coat 11 (Fig. 4). As can be realized from Figs. 3 and 6, front trouser leg panels 12a, 12b of trousers 15 which are immediately exposed to view when the outer garment or coat 11 is in open condition, may be made of a different material than the rear trouser leg panels 15a, 15b of the trousers 15. To this end, there are provided between said front trouser leg panels 12a, 12b of trousers 15 and the respective rear trouser leg panels 15a, 15b intermediate seams 26a, 26b by which the respective front trouser leg panels are connected with the respective rear trouser leg panels. As clearly illustrated in Fig. 6, to front trouser leg panel 12a, which is preferably made of relatively heavy fabric, is joined rear trouser leg panel 15a of a material matching that of the gown or outer garment 11, said panel 15a being in turn fixed at its outer longitudinal side edge 15e by means of seam 24a to the inner face of the rear panel 30a of outer garment 11. Between seam 23c and seam 24a (Figs. 5 and 6), between which is arranged side edge 25a, intermediate lateral panels 26, 27 of the outer garment or coat 11 (Figs. 1 and 4) are positioned.

It is well understood that a similar side edge 25b is provided at the opposite side of side edge 25a of the outer garment or coat 11, as seen in Fig. 5, and that a rear trouser leg panel 15b similar and corresponding to panel 15a and provided with an outer longitudinal side edge 15f, is attached to front trouser leg panel 12b (Fig. 7).

Front trouser leg panels 12a, 12b meet at crotch 28 and are joined together at contiguous edges 12c, 12d in the front of the inner garment member 12 by connecting seam 28a which terminates at the lower end 29 of said fastening means 18.

As seen in Fig. 7, the respective intermediate seams 26a, 26b connecting said front trouser leg panels 12a, 12b with respective rear trouser leg panels 15a, 15b terminate in the crotch 28.

Rear trouser leg panels 15a, 15b in turn are joined together at their contiguous edges 15c, 15d by a seam 15g (see Fig. 7). The rear trouser leg panels 15a, 15b extend upwardly and in superposed position to the rear panel 30a of the coat and meet the inner panel 30 which extends downwardly from the upper coat part and overlies the inner face of the rear panel 30a to form an inner lining and to reinforce the same.

The opposed outer longitudinal side edges 15e, 15f of said rear trouser leg panels 15a, 15b are, respectively, connected by seams 24a, 24b to the

longitudinal side edges of the rear panel 30a of the outer garment or coat 11 (Fig. 7).

It will be well understood that the crotch 28 is curved in downward direction so as to fit the crotch of the human body. Due to the particular shape and the arrangement of the panels forming the outer garment or coat 11, particularly as illustrated in Figs. 2 to 4, the trousers are relatively wider at the lower part than at the upper part.

It is to be noted that the closure means for the inner garment member and outer garment or coat may also be laterally arranged instead of in the center thereof, as herein described. The blouse 16 attached to the trouser 12 may have any desired cut-outs and shape.

It can be seen that there has thus been provided a combination garment which meets all requirements from the practical point of view 20 and in particular with respect to fashion and simplicity of operation.

The combination garment hereinabove described consists of a coat or gown which, when in open position, exposes to view a simulated inner 25 garment member with trousers, said trousers being otherwise not discernible in front or in the back of the coat when the coat is in closed condition, the rear of the inner garment member even not being exposed to view when the coat is in 30 open condition.

It can thus be visualized that according to this invention there has been created a combination garment 10 comprising an outwardly flaring coat 11 consisting of two front panels 23 having each 35 a longitudinal side edge 23a, 23b, a rear panel 30a having longitudinal side edges 24c, 24d, and intermediate lateral panels 26, 27 connected by seams 24a, 24b; 23c, 23d, respectively, to the longitudinal side edges 24c, 24d of said rear panel 40 30a and of said front panels 23; an inner garment member 12 having a crotch 28, said inner garment member 12 comprising a blouse panel 16 having side edges 21 connected to said longitudinal side 45 edges 23a, 23b of said front panels 23, respectively, of said coat 11 and having a lower edge 17, two front trouser leg panels 12a, 12b, two rear trouser leg panels 15a, 15b, said front trouser leg panels and said rear trouser leg panels being each provided with respective contiguous edges 50 12c, 12d and 15c, 15d, a first connecting seam 28a joining together said contiguous edges 12c, 12d of said front trouser leg panels 12a, 12b, a second connecting seam 15g joining together said contiguous edges 15c, 15d of said rear trouser leg 55 panels 15a, 15b, and an intermediate seam 26a, 26b connecting together, respectively, each front trouser leg panel 12a, 12b with a respective rear trouser leg panel 15a, 15b, said first and second connecting seams 28a, 15g and both said intermediate seams 26a, 26b intersecting each other in said crotch 28 of said inner garment member 12, said rear trouser leg panels 15a, 15b being each provided with an outer side edge 15e, 15f and extending upwardly and in superposed position to said rear panel 30a, said front trouser leg panels 12a, 12b being connected to said lower edge 17 of said blouse panel 16 and being each provided with an outer side edge 12e, 12f, said 65 outer side edges 12e, 12f of said front trouser leg panels 12a, 12b being fixed, respectively, to the longitudinal side edges 23a, 23b of said front panels 23 of said coat 11 at the inner face thereof, the outer side edges 15e, 15f of said rear trouser leg panels 15a, 15b being fixed, respec-

tively, to the longitudinal side edges at **24c**, **24d** of said rear panel **30a** of said coat at the inner face thereof.

Thus, one of the most desirable advantages of the invention is attained according to which this combination garment enables the user in emergency, such as air raids and like cases, to be quickly, adequately and entirely dressed. If a hood is attached to the outer garment or coat, head and body of a person will be fully protected and covered.

Although the above improvements relating to a garment have been described with considerable detail and with respect to certain particular form of the invention, it is not desired to be limited to such details since changes and modifications in the form, arrangements, proportions and sizes thereof may well be made without departing from the spirit and scope of the invention in its broadest aspect.

Having thus described the invention, what is claimed as new and desired to be secured by Letters Patent, is:

A combination garment comprising an outwardly flaring coat consisting of two front panels having each a longitudinal side edge, a rear panel having longitudinal side edges, and intermediate lateral panels connected by seams, respectively, to the longitudinal side edges of said rear panel and of said front panels; an inner garment member having a crotch, said inner garment member

comprising a blouse panel having side edges connected to said longitudinal side edges of said front panels, respectively, of said coat and having a lower edge, two front trouser leg panels, two rear trouser leg panels, said front trouser leg panels and said rear trouser leg panels being each provided with respective contiguous edges, a first connecting seam joining together said contiguous edges of said front trouser leg panels, a second connecting seam joining together said contiguous edges of said rear trouser leg panels, and an intermediate seam connecting together, respectively, each front trouser leg panel with a respective rear trouser leg panel, said first and second connecting seams and both said intermediate seams intersecting each other in said crotch of said inner garment member, said rear trouser leg panels being each provided with an outer side edge and extending upwardly and in superposed position to said rear panel, said front trouser leg panels being connected to said lower edge of said blouse panel and being each provided with an outer side edge, said outer side edges of said front trouser leg panels being fixed, respectively, to the longitudinal side edges of said front panels of said coat at the inner face thereof, the outer side edges of said rear trouser leg panels being fixed, respectively, to the longitudinal side edges of said rear panel of said coat at the inner face thereof.

DORA LIEBERT.
